DOUBLE DOOR COORDINATOR

Homer A. Eichacker, Indianapolis, Ind., assignor
to Vonnegut Hardware Company, Indianapolis,
Ind., a corporation of Indiana

Application January 11, 1935, Serial No. 1,304

15 Claims. (Cl. 20—16)

The object of my invention is to produce a device for insuring proper coordination of a pair of mating swinging doors of such character as to be not only efficient but inconspicuous and readily installed.

The accompanying drawings illustrate my invention.

Fig. 1 is a fragmentary perspective of upper adjacent corners of a pair of doors, the adjacent upper door stop and lintel, and my improved device;

Fig. 2 is a plan of my device in association with a pair of doors;

Fig. 3 is a plan, in partial horizontal section, and with the upper cover plate removed, of my device, about three-quarter size and with the several parts in the positions occupied when the normally inactive door is closed;

Fig. 4 is a section on line 4—4 of Fig. 3;

Fig. 5 is a fragmentary plan showing the stop arm in extended position;

Fig. 6 is a plan, similar to Fig. 3, but on a smaller scale, showing the parts in intermediate relation;

Fig. 7 a plan with casing cover removed, of a modification, and

Fig. 8 a fragmentary detail on an enlarged scale of the structure shown in Fig. 7.

In the drawings 10 indicates a normally inactive door, 11 a normally active door with its external astragal 12 and latch bolt 13, 14 the lintel and 15 the upper door stop, these several parts being of normal construction and each generally equipped with an automatic closing device (not shown).

My device comprises a main hollow body 20 with a readily removable cover plate 21. Pivoted upon a stud 22 within casing 20 is a cam 23 which carries a stop arm 24, projectible from the casing 20 by a swing of cam 23. Pivoted upon a stud 25, in casing 20 is a trip arm 26 to be engaged by the normally inactive door. This arm 26 is provided with a finger 27 and a blocking finger 28. Slidably mounted in casing 20, between wall 20' and partition 20'' is a plunger 30, one end of which underlies stop finger 28 and has a one-way engagement with finger 27 and the other end of which is provided with a finger 31 which lies between and has a gear tooth coaction with the fingers 23' and 23'' of cam 23. Any suitable means may be provided to limit the outward swing of stop arm 24. For that purpose I have illustrated a wall 35 at the front of casing 20 to be engaged by the back of cam 23 when arm 24 is projected, as shown in Fig. 5.

A compression spring 37 is interposed between shoulder 30' of plunger 30, and lug 29''' of casing 20.

Preferably secured to the inner face of the normally active door at its upper free corner is a metal wear strip 40 for engagement by the free end of stop arm 24, and at the upper free corner on the inner face of the normally inactive door is a wear strip 41 for engagement with the trip arm 26. These two wear strips are not essential but are desirable to avoid marring of the doors.

Outward swing of trip arm 26 is limited by a stud 42 of casing 20 and engageable by stop finger 28 and this stop finger is engageable by shoulder 30'' of plunger 30.

My device is positioned, as shown in Fig. 1, either mortised into the upper door stop 15 or applied to its under face with the mouth of casing 20 flush with the door-stopping edge of the door stop. When the normally inactive door 10 is closed it engages the trip arm 26 and holds it in the position shown in Fig. 3, so that its finger 27 holds plunger 30, in opposition to spring 37, in the extreme position (to the right Fig. 3) so that its finger 31, acting upon finger 23' of cam 23, holds stop arm 24 parallel with the door plane and within casing 20, so that it is entirely out of view.

With the parts in these positions, the normally active door 11 may be freely opened and closed without causing any operation of my mechanism.

If the normally inactive door be swung toward open position the trip arm 26, because of the action of spring 37 and plunger 30, will follow this door until the left-hand end of plunger 30 passes under the end of finger 27. At this time the parts will be in the positions shown in full lines in Fig. 6. Further opening of the normally inactive door permits spring 37 to drive plunger 30 to the left until stop arm 24 is fully protracted. At this time shoulder 30'' of plunger 30 will have engaged finger 28 of trip arm 26 so as to drive it into engagement with lug 42, and the end of finger 31 of plunger 30 will underlie finger 23'' of cam 23 so that stop arm 24 may not be retracted (Fig. 45). In this position stop arm 24 should lie substantially normal to the normally active door when that door has been swung toward closing position to a position, as indicated in Fig. 2, where the normally inactive door may swing freely without engaging the normally active door, the arrangement being such that, so long as the normally inactive door is open as much as the above-mentioned critical position, the normally active door may not be closed. In installing the device 55

the length of arm 24 will be established to insure the above-described relationship.

In order to close the normally active door, if the normally inactive door is open as much as is indicated in Fig. 2, the normally inactive door must be swung toward closed position to engage arm 26 to swing it to the position shown in full lines in Fig. 6, at which time further closing movement of the inactive door is temporarily stopped, by engagement of the end of finger 27 with the underlying portion of plunger 30, and stop arm 24 is swung to such angular relation with the normally active door 11 that further closing movement of door 11 cams upon arm 24 to drive it close to the position shown in Fig. 3. As the active door 11 approaches closed position plunger 30 will be retracted from beneath finger 27 so that the astragal 12, engaging door 10 may swing said door to closed position, even if the door closing mechanism associated with door 10 should fail to function.

In order to insure proper clearance for the latch bolt 13 I provide, on the inner face of door 10, high enough to be inconspicuous, a finger 50, adapted to engage the inner face of door 11 to move it outwardly enough to permit arm 24 to swing to blocking position.

In general, my coordinator will be used in conjunction with doors equipped with automatic closing devices. The primary traffic will be along the space closed by the normally active door but when heavier traffic occurs the normally inactive door will be utilized. Traffic, however, may proceed in the line of the inactive door even though the active door be closed at the time of approach. Assuming both doors to be closed by individual closing mechanisms (not shown):—A person approaching the normally inactive door may displace it in the opening direction. The initial movement will, by reason of contact with the astragal 12, swing the normally inactive door to the position shown in Fig. 2 and during this time lever 26 will be released so that stop arm 24 may swing to blocking position as shown in Fig. 2. When the pedestrian has passed beyond the normally inactive door it will be automatically returned, swinging clear of the blocked normally active door and will come into contact with lever 26 so as to move plunger 30 to the right and retract stop arm 24 to an angular position where door 11 may act upon it to continue its closing movement.

The extension of plunger 30 to the left of shoulder 30'' (Fig. 3) is not absolutely essential so far as coordination of the door is concerned but if plunger 30 be not extended sufficiently to engage finger 27 when lever 26 is in its retracted position, it is evident that, with the door 10 closed, stop arm 24 would swing outwardly upon each opening movement of door 11, but this outward swing would be limited, by engagement of shoulder 30'' with finger 28 to a position where door 11, upon closing, could act upon arm 24 to swing it inwardly to casing 20. The recurrent partial outward swing of arm 24, upon each opening of the door 11 would be unsightly and it is for this reason that I extend plunger 30 to a position where it will engage finger 27 of lever 26 and thus serve to hold stop arm 24 entirely concealed during all operations of door 11 so long as door 10 is closed. There is preferably a small amount of play between finger 31 and finger 23'' to compensate for slight inaccuracies of position of door 10 in its closed position relative to casing 20.

It will be noted that, owing to the fact that the

swinging elements 26 and 23—24 swing upon vertical axes and cooperate with vertical faces of their respective doors, extreme nicety of positioning of the coordinator vertically of the doors is not important and sagging or raising of the free edges of the doors will have no effect upon proper operation, as would be the case if any portion of the coordinator were dependent upon co-action with the top edge of a door.

By "inner" face of the door I mean the stop 10 engaging face, and by "outer" face I mean that face of the door which is in the direction of opening.

Arm 24 is preferably provided, at its free end with a removable knob 24' rounded at its tip, as 15 shown.

It will be noted, from Fig. 5, that finger 23'' rests upon the top of plunger-portion 31 so that inward swing of the stop arm is prevented until trip arm 26 has been retracted far enough to 20 shift plunger 30 far enough to the right (Fig. 5) to begin the retraction swing of the stop arm. By this arrangement proper blocking of door 11 at a clearance position is insured even though that door at that position is capable of exerting 25 a retraction force upon arm 24.

In the construction shown in Fig. 7 the trip arm 26' is provided with a gear segment 26'' meshing with teeth 300' on plunger 300. This plunger 300 at its opposite end is provided with 30 rack teeth 301 meshing with the gear segment 302 of stop arm 240. When stop arm 240 has been fully projected, the final tooth of rock 301 will pass under the adjacent tooth of the gear segment 302 so as to block retraction swing of 35 the stop arm 240 until trip arm 26' has been moved slightly in retraction direction.

I claim as my invention:

1. A door coordinator for independently movable companion doors comprising a pivotal stop 40 arm to be engaged by a normally used door to block closing movement of said door at a point permitting clearance of a companion normally unused door, a separate movable trip arm to be engaged by said companion door closely adjacent 45 closed position thereof, and means connecting said arms whereby positioning of the stop arm in door blocking position is dependent upon said trip arm.

2. A door coordinator comprising a casing, a 50 stop arm pivoted in said casing for protraction and retraction relative to said casing, a trip arm movably mounted in said casing and a spring-pressed plunger mounted in said casing, said plunger being coordinated with the stop arm 55 to actuate, and be actuated by, said stop arm, and said plunger being coordinated with the trip arm to be actuated thereby in stop-arm retraction direction and to project the trip arm upon release of said trip arm.

3. A door coordinator comprising a casing, a stop arm pivoted in said casing for protraction and retraction relative to said casing, a trip arm movably mounted in said casing about an axis parallel with the axis of the stop arm and a 65 spring-pressed plunger mounted in said casing, said plunger being coordinated with the stop arm to actuate and be actuated by said stop arm, and said plunger being coordinated with the trip arm to be actuated thereby in stop-arm retraction 70 direction and to project the trip arm upon release of said trip arm.

4. A door coordinator of the character defined by claim 2 wherein the plunger is coordinated with the stop arm by interlocking means pre- 75

venting plunger actuation by a stop arm when the stop arm is fully protracted.

5. A door coordinator of the character defined by claim 3 wherein the plunger is coordinated with the stop arm by interlocking means preventing plunger actuation by a stop arm when the stop arm is fully protracted.

6. A door coordinator of the character specified in claim 2 wherein the plunger and trip arm are provided with two pairs of one-way engaging portions coordinated to permit movement of the plunger relative to the trip arm at an intermediate position of protraction of the trip arm, one of said pairs causing initial partial protraction of the trip arm by plunger action and final retraction of the stop arm by final retraction of the trip arm, and the other pair causing final protraction of the trip arm by plunger action and initial partial retraction of the stop arm by initial partial retraction of the trip arm.

7. A door coordinator of the character specified in claim 3 wherein the plunger and trip arm are provided with two pairs of one-way engaging portions coordinated to permit movement of the plunger relative to the trip arm at an intermediate position of protraction of the trip arm, one of said pairs causing initial partial protraction of the trip arm by plunger action and final retraction of the stop arm by final retraction of the trip arm, and the other pair causing final protraction of the trip arm by plunger action and initial partial retraction of the stop arm by initial partial retraction of the trip arm.

8. The combination with a normally active door and a companion normally inactive door, of stop arm pivoted to swing about a vertical pivot to a protracted position blocking closing swing of the normally active door at a position permitting clearance swing of the inactive door, and to an intermediate protracted position when it may be actuated toward retracted position by closing movement of the active door, a movable trip arm separate from the stop arm and arranged to be actuated to retracted position by final closing movement of the inactive door, and a connector between the stop arm and trip arm whereby, upon protraction of the trip arm the stop arm will be protracted to stopping position and complete retraction of the trip arm blocks protraction of the stop arm.

50 9. A combination of the character specified in

claim 8 wherein the connector is a spring-pressed plunger having a gear-like connection with the stop arm.

10. A combination of the character specified in claim 8 wherein the connector is a spring-pressed plunger having a one-way engagement with the trip arm and having a gear-like connection with the stop arm.

11. A combination of the character specified in claim 8 wherein the connector is a spring-pressed plunger having a gear-like connection with the stop arm permitting the plunger to move to a stop-arm-blocking position when the stop arm is fully protracted.

12. A combination of the character specified in claim 8 wherein the connector is a spring-pressed plunger having a one-way engagement with the trip arm and having a gear-like connection with the stop arm permitting the plunger to move to a stop-arm-blocking position when the stop arm is fully protracted.

13. A door-coordinator comprising a casing, a stop-arm pivoted in the casing and protractible and retractible relative thereto, a separate trip-arm pivoted in the casing and protractible and retractible relative thereto, and a spring-pressed plunger geared to the stop arm and to the trip arm.

14. A door-coordinator comprising a casing, a stop-arm pivoted in the casing and protractible and retractible relative thereto, a separate trip-arm pivoted in the casing and protractible and retractible relative thereto, and a spring-pressed plunger geared to the stop arm and to the trip arm, the connection between the plunger and stop arm being such as to block the fully protracted stop arm from retraction until the trip arm has been partially retracted.

15. A door-coordinator comprising a casing, a stop-arm pivoted in the casing and protractible and retractible relative thereto, a separate trip-arm pivoted in the casing and protractible and retractible relative thereto, and a spring-pressed plunger geared to the stop arm and to the trip arm, the connection between the plunger and stop arm comprising a lost-motion arm-blocking means whereby the fully extended stop-arm is blocked against closing movement until the trip-arm is partially retracted.

HOMER A. EICHACKER. 50
